UNITED STATES PATENT OFFICE.

PERCY W. VALENTINE, OF CAMBRIDGE, MASSACHUSETTS, ASSIGNOR OF ONE-HALF
TO LLOYD L. LIVINGSTON, OF ABINGTON, MASSACHUSETTS.

THREAD-HEATING MEANS FOR SEWING MACHINES.

Application filed September 27, 1924. Serial No. 740,407.

To all whom it may concern:

Be it known that I, Percy W. Valentine, a citizen of the United States, residing at Cambridge, in the county of Middlesex and State of Massachusetts, have invented new and useful Improvements in Thread-Heating Means for Sewing Machines, of which the following is a specification.

The purpose of the invention is to furnish 10 in connection with sewing machines using a hot waxed thread, a means for maintaining the thread and its impregnating content of wax in a sufficiently heated condition between the point at which the thread leaves 15 the wax pot or thread-guiding extension thereof and the stitching point. In other words, its purpose is to keep that part of the thread which is exposed to the air prior to the formation of the stitch hot enough to 20 be workable even though the machine should stand idle. The invention is particularly useful and primarily intended for sewing machines designed to stitch leather, as for instance those used in the manufacture of 25 shoes, bags, harness, etc., but, except that the machine is of a type which exposes a length of thread to the air, there is no limitation as to the type, character or make of sewing machine with which the invention may be 30 used, or as to the operation for which it is provided and used.

Before describing the invention I will 35 briefly mention the difficulties in the operation of sewing machines using hot waxed thread and in stitching upon shoes and other leather articles; and in so doing I will refer for illustration to the shoe making art particularly, but without implying thereby any limitation of my claimed invention. In the 40 first place the use of a thread impregnated with hot wax is preferable to using one impregnated or coated with cold wax, for various reasons known to those skilled in the art, the most important of which perhaps is 45 that the hot wax lubricates the thread better, and sets much more quickly, than cold wax, and is of a character to make a much firmer union between the thread and the leather through which the thread passes. 50 The material known by term "hot wax" is a wax which is hard and firm at ordinary temperatures but is liquefiable by heat at a temperature lower than enough to burn the wax or injure the thread. The sewing machines

with which this wax is used are provided 55 with a wax pot through which the thread passes and in which the wax is kept liquid by suitable heating means, usually and preferably an electric heating unit. The thread passes from an outlet in the bottom of the 60 wax pot, the orifice of which is small enough to prevent leakage of the viscous liquid wax, and passes to the needle and other stitch forming instruments of the sewing machine. With the machine with which this invention 65 is concerned a considerable length of the thread extends between the wax pot outlet and the needle in order to give free scope for the action of the stitch forming instruments, and this part of the thread is exposed to rapid cooling by radiation and the 70 conducting effect of air currents. While the stitching machine continues in action, the stitches are formed and set in the work so rapidly that the thread is not exposed to 75 the cool air long enough to permit the wax to harden before the stitches are set; but interruption of the machine affords time for the exposed waxed thread to cool and harden. Such cooling occurs in the case 80 of machines used in shoe making, for instance, in even the short interval of time required to lay down a finished piece of work and pick up and place in position for stitching a new piece of work. It results then 85 that after each stoppage of the machine the operator, just before commencing on the next piece of work, must seize the end of the thread and pull it out far enough to bring a heated length to the needle. This results 90 in wasting all the thread between the needle and the wax pot every time the thread is thus pulled out; and the amount so wasted each time is from a foot to a foot and a half. If the operator forgets to pull away the 95 hardened thread, the result is difficulty in passing the stitches through the work and an inferior or spoiled piece of work. Thus in order to produce satisfactory work, a wastage of thread is necessary which in the 100 course of a year amounts to a very substantial item for each machine in use. There is also an appreciable reduction in the output of the operator due to the time required for thus drawing off the chilled parts of the 105 thread.

The difficulties and objections above referred to in connection with machines us-

ing hot waxed thread have been avoided through my invention by the application to the machine of a device which throws a concentrated beam of radiant heat upon the 5 length of thread intervening between the needle and the wax pot, and preferably also on a part of the wax pot itself, or of an extension of the wax pot through which the 10 thread passes before emerging into the open air. The source of heat is of a character and placed in such a location that it is not a menace to the operator's safety and comfort, but it has a heat-giving capacity sufficient to keep the exposed thread at such 15 a temperature that the wax has the desired fluidity. I will now proceed to describe a specific embodiment of the invention in detail, with reference to the accompanying drawings which show a commercial type of 20 sewing machine having my heating attachment applied thereto. The invention which I claim consists in the combination of a sewing machine of any type and a heater of the general character above indicated, but of any 25 desired specific type, arranged and cooperating 75 to the effect above indicated.

In the drawings:

Figure 1 is a side view of a sewing machine with my heating attachment applied 30 thereto;

Fig. 2 is a front elevation of the sewing machine and associated heating attachment;

Fig. 3 is a view similar to Fig. 2 and on a larger scale, but omitting the frame of the 35 sewing machine;

Fig. 4 is a sectional view of a suitable form of heater adapted to project a beam of radiant heat;

Fig. 5 is a perspective view of an alternative form of heating element adapted to be 40 used as a part of the heat projector shown in Fig. 4 and in substitution for the heating element there shown.

Like reference characters designate the 45 same parts wherever they occur in all the figures.

The machine and the stitch forming instrumentalities shown in Figs. 1, 2 and 3 are those of a commercial machine put out for 50 stitching leather bags. The numeral 11 represents the frame of the machine, 12 the table or work-rest, 13 the presser-foot, 14 the needle, and 15 and 16 other instruments co-operating with the needle in a well-known 55 way to form stitches. 17 represents the wax pot which is secured to the upper part of the frame of the machine, as here shown by bracket 18. The thread 19 passes into the top of the wax pot around a tension guide 60 20 and extends through a tube 21, which forms an extension of the bottom of the wax pot, and emerges through a guide 22 having an orifice of a proper size to permit passage of the thread and exclude passage of the hot 65 wax. The wax pot may be heated by any

suitable means, such as a gas flame but preferably by an electrical heating unit which may be of any sort now used or suitable for the purpose. The outer end of such a unit is shown in Fig. 2 and a switch 23 is there 70 shown as applied to the unit. A cable 24 contains the wire circuit for the heating unit and leads from any suitable source of electrical energy, for instance a socket in an electric lighting system. 75

As thus far described the machine is not essentially different from hot waxed thread sewing machines now on the market and contains nothing new except the tube 21 which extends from the pot and forms, in effect, a 80 part thereof, cooperating with the wax pot proper and the heating attachment in a manner presently described. For the purpose of this description the specific sewing machine herein shown and described may be 85 considered as typical of any and all machines equipped for stitching with a hot waxed thread, and in which the thread is exposed to the surrounding air in its course to the 90 stitch forming means.

The section of the thread lying between the outer guide 22 and the needle is exposed to the air and is subject to a rapid cooling effect. It is designated by the reference character 19^a. With the machines heretofore used, this length of thread becomes cool and stiff when the machine is allowed to stand idle for any except the briefest length of time. This is the part of the thread which must be drawn off, as previously mentioned, far enough to substitute a hot length of thread from the wax pot just before starting the machine again after an idle period. My invention comprises a means for keeping the exposed thread 19^a hot and in permanent condition for sewing during any idle period no matter how prolonged, and in carrying the invention into effect, I have provided a heating attachment which consists of a heating unit and a projecting reflector. Said unit and reflector combination are shown in detail in Figure 4. The unit is a coil of high 105 resistance wire 25 wound around a core 26 and connected to lead wires 27 and 28. The reflector is designated 29. It is of generally parabolic form; in other words is a projecting reflector of a type having a focus and so formed that it will reflect, in a concentrated beam, rays emitted from a source of heat placed at or near the focus. It is preferably formed with a sleeve portion 30 at 110 its apex in which the heating unit is fitted and secured. The heating unit is thereby mounted at the focal point of the reflector and in the region adjacent thereto. This combined heating unit and reflector embodies principles well-known and already used to project light or heat rays in a beam, 115 in other environments. It may be embodied 120 in other forms than that shown; for instance 125

with the substitution of the heating unit 31 shown in Fig. 5 in place of the heating unit 25, or with reflectors adapted to cause greater or less concentration of reflected 5 heat rays in the space occupied by the exposed thread. The alternative heating unit shown in Fig. 5 is one of a well-known commercial character in which a high resistance conductor is incased in a shell, whereby it 10 gives off heat merely and does not glow. Either unit may be used in place of the other according as the light and the intense heat of the exposed wire in the heater 25 is an advantage or a disadvantage.

15 The heat projector, as I may now call the combined heating unit and reflector, is mounted on or beside the sewing machine in any convenient way, for example by means of a bracket 32 attached to the side 20 of the machine frame and having a sleeve portion to contain the sleeve of the reflector, and in a position where it is out of the way of the operator but directs its beam of heat over the space which is crossed by the exposed length 19^a of the thread. The terminals of the heating unit are connected to the wires in a cable 33 and these wires in turn are adapted to be connected by means 25 of a switch 34 with the main wires in the cable 24.

30 This mode of mounting the projector and connecting its heating unit in the electric circuit, illustrates one of many possible ways in which the projector may be mounted and 35 connected, within the skill of persons skilled in the art, and within the protection which I claim. If desired the mount which holds the projector may be equipped with provisions for adjustment, but I have not 40 thought it necessary to illustrate such provisions as they are not an essential feature of the invention.

45 By means of the projector I am able to direct a heat beam high enough in temperature and throwing enough heat upon the exposed thread, to maintain the thread always at the temperature where its content and coating of wax is soft and fluid enough for the proper stitching. This result may 50 be achieved even though the temperature of the source of heat itself is not great enough to emit light, by properly designing the reflector so that enough of the heat rays will impinge on the thread. I have found that 55 with the use of a parabolic reflector and either type of heating unit shown in these drawings, I can keep the thread warm enough for the purpose but without injuring it or the wax upon it, and without causing 60 discomfort to the operator's hands when exposed to the beam.

65 A further feature of the invention to which I direct attention is the coaction of the extension tube 21 with the wax pot proper and the heat projector. This tube

and its connection with the wax pot are large enough internally to contain a body of wax which flows freely from the pot. Its end nearer the needle extends into the heat beam from the heat projector. Thus it is heated 70 at both ends; one end being heated by the radiant heat from the projector and the other end by conduction from the walls of the wax pot proper and the contained body of wax. The heat thus delivered to the 75 extension tube from both of its ends is enough to keep the wax in this tube hot enough for the purposes of satisfactory stitching. The protection which I claim is not altogether limited to such an extension tube however, for satisfactory results may also be obtained even with the omission of this tube and although the projected heat beam may not be as wide as the entire space between needle and the thread outlet from the wax pot.

80 It will be apparent that, as the exposed thread is thus kept with its content and coating of wax in a suitable plastic condition, no matter how long the machine may stand idle, it is always in condition to resume stitching at once after an idle period, and the operator does not need to draw off the exposed length of thread before commencing to stitch. In this way the thread 85 formerly wasted is used and the operator's time is saved.

90 What I claim and desire to secure by Letters Patent is:

1. The combination with a sewing machine and a heated pot of wax through which the thread passes in its course to the stitching instruments, of a heat projector arranged to direct a beam of radiant heat upon the thread between said wax pot and stitching instruments.

100 2. A sewing machine using a hot waxed thread combined with a heat projector arranged to direct a beam of radiant heat on the exposed thread adjacent to the stitch forming instruments of the machine.

110 3. In a sewing machine, a wax pot arranged to receive the sewing thread in its passage to the stitch forming instruments of said machine, means for heating said wax 115 pot and the contained wax, and means for throwing a beam of radiant heat upon the region, between said wax pot and the stitching point, in which the needle and other stitch forming instruments of the machine 120 operate on the thread to form stitches.

125 4. In a sewing machine, a wax pot arranged to receive the sewing thread in its passage to the stitch forming instruments of said machine, means for heating said wax pot and the contained wax, and means for throwing a beam of radiant heat upon the region, between said wax pot and the stitching point, in which the needle and other stitch forming instruments of the machine 130

- operate on the thread to form stitches, said wax pot having a tubular extension through which the thread passes and the outer end of which extends into said beam.
5. A sewing machine adapted to stitch with a hot waxed thread, a wax pot associated with said machine through which the thread is adapted to pass on its way to the stitching point, means for heating said wax pot and the contained wax, the wax pot having an extension through which the thread passes and in which wax is contained in communication with the main body of wax in the pot, and a heat projector comprising a source of heat, and a projecting reflector surrounding said source, arranged to direct a concentrated heat beam upon the end of said extension tube and the space through which the thread passes between said extension tube and the stitching point.
6. In a sewing machine, stitch forming means, a heated wax pot, through which the thread for stitching is caused to pass on its way to said means, there being between the outlet from the wax pot and said means an open space which the thread crosses and in which the thread is exposed to the cooling effect of the surrounding air, and means for heating the thread in said open space.
- 30 7. In a sewing machine, stitch forming means, a heated wax pot, through which the thread for stitching is caused to pass on its way to said means, there being between the outlet from the wax pot and said means an open space which the thread crosses and in which the thread is exposed to the cooling effect of the surrounding air, and a heat projector arranged at one side of the course of the thread and constructed to project a concentrated beam of radiant heat upon the thread crossing said space.
8. In a sewing machine, stitch forming instruments, a heated wax pot, through which the thread for stitching is caused to pass on its way to said instruments, there being between the outlet from the wax pot and said instruments an open space which the thread crosses and in which the thread is exposed to the cooling effect of the surrounding air, an electrical heating unit at one side of the course of the thread, and a projecting reflector constructed and arranged in association with said unit to project a concentrated beam of radiant heat from said heating unit upon the thread in said open space.
9. The combination with a sewing machine and a heated pot of wax through which the thread passes in its course to the stitching instruments, of a heat projector comprising a projecting reflector and a source of heat substantially at the focal point of said reflector, arranged to direct a beam of radiant heat upon the thread between said wax pot and stitching instruments.
10. In combination with a sewing machine having a heated wax pot, means for heating the thread used by said machine where such thread is exposed to the cooling effect of the outer air; said means consisting of a heating unit and a reflector arranged to reflect heat rays from said unit in a concentrated beam upon the thread so exposed.

In testimony whereof I have affixed my signature.

PERCY W. VALENTINE.
